[57] CLAIM

The ornamental design for a holder for advertising display or the like, as shown and described.

DESCRIPTION

FIG. 1 is a perspective view of a holder for advertising display or the like showing my design;

FIG. 2 is a front elevational view thereof;

FIG. 3 is a top plan view taken from line 3—3 of FIG. 2;

FIG. 4 is a left side elevational view taken from line 4—4 of FIG. 2;

FIG. 5 is an elevational view taken from line 5—5 of FIG. 2;

FIG. 6 is a right side elevational view taken from line 6—6 of FIG. 2;

FIG. 7 is a rear elevational view thereof; and

FIG. 8 is a large right side elevational fragmentary sectional view taken from line 8—8 of FIG. 1.

The broken line showing of the wall is for illustrative purposes only and forms no part of the claimed design.
